Milwaukee, Wisconsin

UNITED STATES PATENT OFFICE.

CHARLES F. CUNO, OF MERIDEN, CONNECTICUT.

SWITCH.

1,378,660.

Specification of Letters Patent. Patented May 17, 1921.

Application filed February 12, 1920. Serial No. 358,042.

To all whom it may concern:

Be it known that I, CHARLES F. CUNO, a citizen of the United States of America, residing at Meriden, Connecticut, have invented 5 a new and useful Switch, of which the following is a specification.

My invention relates to electric switches and particularly of a type designed to carry heavy current such as a starter switch for 10 automobile self-starters, so-called.

The object of my invention is to provide a simple construction which will permit the switches to be economically and rapidly produced, the simplicity and cheapness 15 of the structure in no way sacrificing the effectiveness of the same as a switch mechanism.

In the drawings:

Figure 1 is a plan view of a portion of 20 the switch mechanism.

Fig. 2 is a section on the line 2—2 of Fig. 1.

Fig. 3 is a side elevation.

Fig. 4 is a sectional view.

25 1 represents the main portion of the switch casing which constitutes a housing. 2 is a flange around the edge of the housing 1. 3 is a cap or cover plate. These parts may be struck up from sheet metal. 4 is a sheet metal channeled member which is arranged to rest in the bottom of the housing 1 and which extends diametrically across the center. 5 represents a piece of insulation in the form of a channel arranged to rest snugly 30 within the channel 4. 6 is a second piece of insulation which is channeled in form and arranged to rest in the bottom of the channeled insulation 5. 7—7 are terminal pieces, the heads of which are arranged to rest in the bottom of the channeled insulation 6 while the shanks pass through the channeled insulation 5, the metal channel 4 and the housing 1, the shanks of each of 35 said terminal pieces being insulated from the metallic channel 4 and the housing 1 by suitable insulating pieces. 7^a represents an insulating washer. 8 represents a nut threaded on to the shank of each insulating piece to hold the several parts firmly assembled in operative position. 9 represents a tube mounted on the cover plate 3. 10 is a cap slidably mounted on the outer end of the tube 9. 11 is a switch blade which 40 may be of laminated form, the same being mounted upon but insulated from the lower

end of a plunger 12. The upper end of the plunger 12 is connected with the cap 10 and a suitable spring within the tube 9 serves to cause the plunger 12 to stand in a retracted position to hold the switch 60 blade 11 in the position shown in Fig. 2 and normally out of contact with the terminal pieces 7—7. The switch blade stands within the channel formed by the insulation 5 and is held thereby in proper position to engage the terminal pieces 7—7 when the cap 10 is depressed, the inner side walls of the channeled insulation 5 acting to guide said switch blade. Suitable electric connections may be made with the shanks of 65 the respective terminal pieces 7—7 which act as binding posts. When pressure is applied to the cap 10, the switch blade is forced downwardly so as to act as an electric bridge or connection between the two terminal 70 pieces 7—7 and close the circuit. When pressure on the part 10 is released, the spring within the sleeve 9 retracts the cap 10 and the switch blade so as to open the 75 circuit.

From the foregoing it will be seen that an exceedingly simple and yet effective switch construction is afforded, most of the parts of which may be formed from stampings and hence may be rapidly produced at 80 a minimum of expense.

What I claim is:

1. In a switch of the character described, a housing, a metallic channeled piece resting in the bottom thereof, a channeled piece 90 of insulating material resting in said metallic channel and supported thereby and projecting upwardly therefrom, a plurality of terminal pieces located in the bottom of said insulating channel, each of said terminal pieces having a shank extending through said parts but insulated therefrom with means on each of said shanks for holding all of said parts assembled, a switch blade located in the channeled insulating 95 piece and guided thereby and arranged to electrically bridge the said terminals when moved into contact therewith, and means for carrying said blade and for moving the same into and out of contact with said terminal pieces.

2. In an electric switch, a housing, a metallic channeled piece located therein, a channeled piece of insulating material resting in the first mentioned channeled piece and sup- 110

ported thereby, two terminal pieces resting in the channel piece of insulating material, with means for furnishing electric connection with said terminal pieces from outside 5 said housing, a blade switch arranged longitudinally in the channeled piece of insulating material and arranged to connect the two terminal pieces, a cap for the housing and an operating means carried by the cap 10 and associated with said blade switch for operating the same.

3. In an electric switch, a housing, a channel of insulating material secured therein, a plurality of terminal pieces located in said 15 channel, a blade switch positioned longitudinally between the side walls of said channel and above said terminal pieces, and means for moving said blade into and out of contact with said terminals to electrically connect and disconnect the same, and a metallic channel member located in said housing and supporting and reinforcing the side walls of the insulating channel.

4. In a switch of the character described, 25 a housing, a strip of insulating material extending transversely across the housing adjacent to the base of the same and having an outstanding flange at one edge, a metallic strip located between said insulating strip 30 and the bottom of said housing, one edge of said metallic strip being shaped to support said flange, a plurality of spaced terminal pieces adjacent the opposite ends of said strips, each of said terminal pieces having a 35 shank extending through said parts and through the housing and insulated therefrom, a switch blade extending over said terminal pieces and located adjacent said flange of the insulating strip whereby the 40 latter will hold said blade in substantial alinement with said terminals, and means for moving said blade up and down.

5. In a switch of the character described, 45 a housing, two stationary contacts spaced apart from each other in the inside of said housing and insulated therefrom, said contacts having parts projecting through said housing, means on said parts for securing said contacts in the housing, a spring-pressed 50 contact member reciprocable in said housing for contacting with said stationary contact members, and a strip of sheet insulating material supported in said housing and alongside of said contacts and serving to

guide said spring-pressed contact member in 55 its reciprocation in the housing.

6. In a device of the character described, a channel-shaped member, spaced apart stationary contact members in said channel-shaped member and insulated therefrom and 60 having parts projecting through said channel-shaped member, a spring-pressed contact member reciprocable in a direction toward and away from the stationary contact members in said channel-shaped member 65 and adapted to contact with said stationary contact members, and a strip of insulating material supported in said channel and extending alongside of said contacts for preventing said spring-pressed member from 70 contacting with said channel-shaped member during its reciprocation.

7. In a device of the character described, a cover member having a rod reciprocable therethrough, a bridging contact member carried by said rod, a spring for urging said bridging contact member in one direction, a channel-shaped member below said cover and in substantial alinement with said bridging contact member, opposed stationary contact members in said channel-shaped member and having parts extending therethrough and insulated from said channel member, and a strip of insulating material mounted in said channel and serving to prevent said bridging contact member from contacting with said channel-shaped member during the reciprocation of the bridging contact member.

8. In a device of the character described, 90 a cover member having a rod reciprocable therethrough, a bridging contact member carried by said rod, a spring for urging said bridging contact member in one direction, a channel-shaped member below said cover 95 and in substantial alinement with said bridging contact member, opposed stationary contact members in said channel-shaped member and having parts extending therethrough, and a channel of insulating material supported in said channel-shaped member and serving to insulate said stationary contact members and said bridging contact member from the channel-shaped member during the reciprocation of the 100 bridging contact member.

CHARLES F. CUNO.
